(57) **CLAIM**

The ornamental design for a standard holder and standard for insitu turbidity measurement device, as shown and described.

DESCRIPTION

FIG. 1 is a front perspective view of our design.

FIG. 2 is an elevation view showing the front side of our design.

FIG. 3 is an elevation view showing the rear side of our design.

FIG. 4 is an elevation view showing the right side of our design.

FIG. 5 is an elevation view showing the left side of our design.

FIG. 6 is a plan view showing the top side of our design.

FIG. 7 is a plan view showing the bottom side of our design; and,

FIG. 8 is an exploded perspective view showing the components of our design.

The broken lines showing an attached component is included for the purpose of illustrating use and environment and form no part of the claimed design.
